UNITED STATES PATENT OFFICE.

WILLIAM R. DAY, OF CLEVELAND, OHIO.

PISTON.

Application filed December 13, 1924. Serial No. 755,609.

REISSUED

To all whom it may concern:

Be it known that I, WILLIAM R. DAY, a citizen of the United States, residing in Cleveland, county of Cuyahoga, and State of Ohio, have invented a new and useful Improvement in Pistons, of which the following is a specification.

My invention relates to the construction of pistons.

10 One of the objects of my invention is a light weight piston.

Another object is to eliminate distortion of the bearing portion of pistons.

Another object is a piston which wears 15 the wall of a cylinder evenly.

Another object is to eliminate the scoring of the cylinder wall.

Another object is to prolong the life of 20 pistons as well as of cylinders in which the pistons operate.

Another object is a piston of low cost of production.

It is well known in the art that a piston should be as light in weight as possible and 25 should create as little friction as possible when it operates in a cylinder.

It is also well known in the art that certain portions of the usual pistons wear 30 much faster than other portions, indicating thereby that too much friction is created by these fast wearing portions.

To eliminate, or at least mitigate, this friction, the piston shell has, previously, been relieved or slit but such expediences 35 not only reduce the area of the bearing surface of the piston but also add materially to the cost of production of the piston.

When these portions are relieved, the 40 bearing surface of the piston is unequally distributed, thereby causing the cylinder wall to wear uneven and out of round and quite frequently score the cylinder because 45 foreign matter can readily and easily wedge onto the bearing surface from these relieved portions; all of which causes a leaky piston and other disadvantages in a short time.

After experimentation, I have found that 50 the action of the rod, particularly connecting rod or pitman, exerts unequal pressure on the piston through the piston-pin bosses and that the shell of the piston, as previously made, is thereby distorted to such an extent that some portions of this shell are forced against the cylinder wall harder than 55 other portions, thereby causing the trouble mentioned.

Upon further experimentation, I have found that the shell of a piston is not so distorted when the boss or bosses, by means of which the piston is connected to the rod, 60 is as free as possible from the shell of the piston.

Therefore, by eliminating, as far as possible, any connection of the boss and the shell, I eliminate the distortion of the shell 65 as well as the cost of correction of these distortions, thereby producing a better piston at less cost than heretofore.

And furthermore, I provide abrupt shoulders where the bearing portions of the 70 shell join the relieved portions thereof, thereby eliminating the scoring of the cylinder.

One structure for attaining my objects and embodying the features of my invention is illustrated in the accompanying drawing in which:—

Fig. 1 is a perspective view of a piston embodying my invention and showing the general appearance of the piston as a whole. 75

Fig. 2 is a partial section, taken on a vertical plane indicated by the line 2—2 in Fig. 1, showing clearly the relation of the piston-pin bosses to the shell of the piston and to the wall of the cylinder. 80

Fig. 3 is a partial section, taken on a vertical plane indicated by the line 3—3 in Fig. 1, showing clearly the relation of the connecting portion and the bearing portions 85 of the shell.

Fig. 4 is a section, taken on a horizontal plane indicated by the line 4—4 in Fig. 1, showing the horizontal relation between the piston portions.

Similar reference characters refer to 90 similar parts throughout the views.

The piston shown in the accompanying drawing is composed, principally, of the upper bearing portion A, the lower bearing portion B, the connecting portions C, 100 and the bosses D.

The upper bearing portion A fits the wall 9 of the cylinder all around and is closed at the top by the wall 10 and is provided with the grooves 11 for piston rings 105 as usual in pistons.

It is observed that the circumferential wall of the portion A has the wider portions 12 above the portions C and the narrower portions 13 above the bosses D. This 110 is for the purpose of providing more bearing surface on those sides of the portion A

where the usual connecting rod exerts an angular pressure on the piston, thereby prolonging the life of the piston as well as wearing the wall of the cylinder more evenly and thereby also prolong the life of the cylinder.

The lower bearing portion B also fits the wall 9 all around and is provided with the circumferential rib 14 on the bottom.

- 10 Each of the connecting portions C extends part way around the piston circumferentially and is disposed between the portions A and B longitudinally and merges into both of them and connects them to each other. The longitudinal ribs 15 are provided to stiffen the portions C as well as the piston as a whole.

It is observed that the outer circumferential surface 16 of each portion C is disposed below the outer circumferential surface of the portions A and B and that the shoulders 17 and 18 are abrupt; the purpose thereof will appear presently.

Each of the bosses D has the bore 19 for a piston-pin or for a bushing therefor. Each of the bosses D is supported on the portion A and is free of any connection with the portion B.

Each of the bosses D is connected to the portion A by the circumferential rib 20 extending upward and merging into the portion 13 and by the two radial ribs 21 extending upward and merging into the wall 10 and into the rib 20. Thereby providing a substantial support for each of the bosses D without connecting them to the portion B and carrying the main point of such support up to the wall 10 so that most of the unequal stresses brought on the bosses D are transmitted to this wall 10 and to the stiffer wall of the portion A without materially effecting either of the portions A and B.

I prefer to use the two radial ribs 21 as shown to more effectively counteract the distortive action on the bosses D and to transmit as much as possible of the stress caused by the action of the connecting rod on the bosses directly to the top wall 10 of the piston. This two rib arrangement also stiffens the rib 20 and thereby prevents this distortive effect from being transmitted to the bearing portions of the piston.

It is observed that the outer circumferential surface 22 of the rib 20 is disposed below the outer circumferential surface of the bearing portions A and B and that the shoulders 23 are abrupt similar to the shoulders 18 and 17 previously described.

These abrupt shoulders on the portion A have a tendency to scrape the surplus lubricant off of the wall of the cylinder on the down stroke of the piston. A certain quantity of this scraped off lubricant adheres to these shoulders during this down stroke and is deposited again on the cylinder wall on

the upstroke. Some of this scraped off lubricant also travels downward on the ribs 20 and finds its way onto the piston-pin and thereby helps to lubricate the same. Some of this scraped off lubricant also travels downward on the portions C and thereby helps to lubricate the portion B. When too much lubricant is splashed or otherwise put on the cylinder wall, the shoulders 23 and 17 scrape it off on the downstroke while the shoulders 18 scrape it off on the up stroke. In either case of such scraping off, the surplus lubricant finds its way into the interior of the piston and drips off into the crank case or elsewhere.

The above shoulder arrangement prevents excessive lubricant from entering the cylinder above the piston and thereby economizes in lubricant consumption as well as aiding in the efficiency of the power development of the engine and at the same time adequately lubricate the cylinder wall.

These abrupt shoulders also effectively scrape all foreign substances from the cylinder wall, similar to the scraping process just described, thereby preventing the scaring of the cylinder.

The manner of supporting the bosses D on the piston, as set forth, prevents the connecting rod, or other rod, acting on these bosses from distorting the bearing portions of the piston and therefore, such a piston requires no relieving or other expediencies and the surfaces 16 and 22 need no machining.

In the elimination of this relieving and machining, augmented by the light weight structure possible with my invention, and further augmented by the saving in lubricant and by increased power, I provide a piston which is very economical of production and very efficient in operation and in action.

The wide surfaces 12 adjacent the narrower surfaces 13, both of which surfaces bear on the cylinder wall, all around, wears the cylinder wall evenly and thereby prevents leaky pistons and prolongs the life of the cylinder as well as of the piston.

I am aware that modifications may be made in the structure of the piston as well as in the arrangement of the elements thereof; therefore, without limiting myself to the precise construction and arrangements shown and described,

I claim:—

1. A piston comprising, an upper bearing portion, a lower bearing portion spaced from said upper bearing portion, two narrow portions connecting said upper and lower bearing portions, piston-pin bosses integral with said upper bearing portion, and said bosses free from said lower bearing portion to prevent the distortion of said lower bearing portion when said bosses are

distorted by a piston-pin extending through said bosses out of alignment with elements co-operating with the piston-pin.

2. A piston comprising, an upper bearing portion closed by a top wall, a lower bearing portion, connecting portions between said upper and said lower bearing portions, piston-pin bosses disposed intermediate of said connecting portions and free from said lower bearing portion, rib means connecting each of said bosses to said upper bearing portion, and the outer surfaces of said connecting portions and of said rib means below the outer surface of said bearing portions and defined by abrupt shoulders to lubricate the wall of the cylinder in which the piston operates without permitting excessive lubricant to enter this cylinder above the piston.

3. A piston comprising, an upper bearing

portion closed by a top wall, a lower bearing portion, connecting portions between said upper and said lower bearing portions, piston-pin bosses disposed intermediate of said connecting portions and free from said lower portion, said upper bearing portion wider above said connecting portions than above said piston bosses to compensate for angular pressure on the piston, rib means connecting each of said bosses to said upper bearing portion, and the outer surface of said connecting portions and of said rib means below the outer surface of said bearing portions and defined by abrupt shoulders to lubricate the wall of the cylinder in which the piston operates without permitting excessive lubricant to enter this cylinder above the piston.

WILLIAM R. DAY.
